FOREIGN PATENT DOCUMENTS

FR 2293277 7/1976

Primary Examiner — Phillip S Hyder(74) *Attorney, Agent, or Firm* — Michael Best & Friedrich LLP(57) **CLAIM**

We claim the ornamental design for a saw, as shown and described.

DESCRIPTION

FIG. 1 is a perspective view of a saw showing our new design;
 FIG. 2 is a left side elevation view thereof;
 FIG. 3 is a right side elevation view thereof;
 FIG. 4 is a front end elevation view thereof;
 FIG. 5 is a rear end elevation view thereof;
 FIG. 6 is a top plan view thereof; and,
 FIG. 7 is a bottom plan view thereof.
 The broken lines depict portions of the saw in which the design is embodied that are not considered part of the claimed design.

1 Claim, 5 Drawing Sheets---
